UNITED STATES PATENT OFFICE

ALEXANDER S. MACKENZIE, OF HOUSTON, TEXAS, ASSIGNOR TO CLAYTON GIN COMPRESS COMPANY, OF HOUSTON, TEXAS, A CORPORATION OF TEXAS.

TORQUE DYNAMOMETER

Application filed February 3, 1928. Serial No. 251,625.

This invention relates to new and useful improvements in torque dynamometers.

An important object of the invention is to provide a torque dynamometer with a construction adapting it to be effectively employed as a coupling device for driving and driven elements so that it will serve the function of a safety device to prevent injury to the driven element or device.

Another important object of the invention is to provide indicating means for a baling press including baling rolls, and which will not only indicate in terms of torque, the resistance offered by the baling rolls and other parts of the press to the power device; but one which will also indicate in a highly satisfactory manner, the density of the baled material during all stages of the baling operation.

A further important object of the invention resides in the provision of a simple and efficient torque dynamometer in which the number of parts are reduced to a minimum and the arrangement is such that certain parts provide for the protection of certain other parts.

Other objects and advantages of the invention will become apparent during the course of the following description.

In the drawings forming a part of the description and wherein like numerals are employed to designate like parts throughout the several views,

Figure 1 is a front elevation of a round bale press with the invention applied thereto.

Figure 2 is an enlarged top plan of my improved torque dynamometer.

Figure 3 is a side elevation of the same; parts thereof being broken away to show the interior construction.

Figure 4 is a vertical transverse section of the same.

Figure 5 is a similar view of a modified form of the invention.

Figure 6 is an enlarged transverse section of one of the connections between the driving and driven elements, and

Figure 7 is an enlarged fragmentary view of part of the indicator mechanism.

Referring now more particularly to the

drawings, a round bale press is indicated in general by the letter A and is of identically the same construction as the press disclosed in my copending application Serial No. 246,491, filed Jan. 13, 1928, so that a detailed description thereof in the present case is not essential. It is sufficient for an understanding of the present invention to note that the press A is of the round bale type and in this particular instance includes twelve baling rolls, each of which is positively rotated by a series of power elements all of which derive power from a counter shaft B, having keyed thereto, a sprocket which is driven by means of a sprocket chain C operating over a sprocket loosely mounted upon a drive shaft and having an extended hub D to cooperate with my improved torque dynamometer indicated in general by the letter F.

This drive shaft is secured to a driven part G of a manually controlled clutch, the co-operating driving part H of the clutch being loosely mounted upon a drive shaft 11 to be driven by a pulley I which may be continuously driven from a suitable source to drive the press through the mechanism just described. A hand lever J is suitably mounted to engage and disengage the clutch parts G and H in the usual manner.

My improved torque dynamometer F comprises a driving plate or disk 9 having a hub 10 extended outwardly thereof and secured to the drive shaft 11 as by a set screw 12. This drive shaft 11 is connected to the clutch part G, as will be readily understood. The drive plate 9 is provided with a plurality of apertured inwardly extending bosses 13 spaced equidistantly around the disk. A pin 14 is doweled in each boss 13 and has its inner end extending inwardly beyond the boss as clearly shown in Figure 4.

A driven plate or disk 15 is mounted on the shaft 11 in spaced relation to the plate 9 and is provided with an inwardly extending hub 16 secured to the extended hub D of the sprocket heretofore described as being loosely mounted upon the drive shaft 11 by means of the bushing 17. This driven plate 15 is likewise provided with the same number of inwardly extending apertured bosses 18 as

the driving plate 9, and pins are likewise doweled into these bosses just as are the pins 14 of the driving plate for pivotally mounting a plurality of cages 19 upon the driven plate. The outer end of each cage is internally screw threaded for the reception of a guide collar 20 centrally apertured for sliding engagement with a bolt 21. This bolt has its inner end within the cage threaded 10 for the reception of a head 22, which, as best shown in Figure 6, is provided with a pair of diametrically arranged outwardly extending projections 23 which operate in slots 24 provided at diametrically opposite points 15 in the cage 19. This construction prevents turning of the plunger heads within the cages and also limits the relative movement of the drive and driven plates 9 and 15, as well as 20 to prevent excessive compression of a coiled spring 25 surrounding each bolt 21 and having its ends abutting the collar 20 and the head 22 of the plunger. The tension of the springs 25 is preferably such that the drive plate 9 rotates the driven plate 15 through 25 these springs without causing the projections 23 to abut the ends of the slots 24, and the spring tension can obviously be varied by adjustment of the collars 20.

The outer end of each bolt 21 terminates 30 in an eye 26 which is mounted upon its respective pin 14 and is removably retained thereon by means of a washer 27 and a cotter pin 28 or the like. The cages 19 are similarly connected to pins mounted in the bosses 18 35 of the driven plate 15. Although, one or more of these spring devices will be sufficient to form a yielding connection between the drive and driven plates, as illustrated, four such devices are employed in the present 40 illustration.

In order to record the relative movement of the plates 9 and 15, or in other words, the torque resistance of the driven element 15, a member 29 in the form of a ring is mounted 45 upon the peripheries of the drive and driven disks 9 and 15 to span the space between these members and to cover the spring devices arranged between them. This ring 29 is provided on its inner periphery adjacent one 50 edge with axially extending grooves 30 for sliding engagement with keys or splines 31 secured to the periphery of the driven disk 15 at points spaced equidistant around its periphery, as shown in Figure 3. It will, 55 therefore, be seen that with this construction the ring 29 will rotate with the driven disk 15 and yet may slide axially thereof on the splines 31.

In order to impart axial movement to the 60 ring 29 upon relative movement of the drive and driven plates, it is equipped with a plurality of diagonally arranged cam slots 32 in which operate projections 33 carried by the eyes 26 of the bolts 21. Each of these projections is equipped with the head 34 adapt-

ed to be arranged exteriorly of the ring and in practice these projections 33 are simply headed studs having threaded inner ends adapted to screw into the eye portions 26 of the bolts.

The periphery of the ring 29 is provided with a circumferentially extending groove 35 formed by a pair of spaced outstanding annular flanges. Within this groove there is adapted to operate, a shoe 36 which is connected, by means of a crank 37, to an indicator shaft 38 mounted in a bearing 39 of a stand 40 which may be suitably secured to the base of the press or any other suitable foundation. The outer face of this stand is equipped with vernier graduations 41 for co-operation with a pointer 42 secured to the shaft 38.

The modification shown in Figure 5 is identically the same as that shown in Figure 4, 85 but, is designed to serve as a coupling between a divided shaft, the section 11 thereof being the driving section, whereas the section 43 is the driven section of the shaft. Instead of the driven plate 15 being mounted 90 loosely upon the shaft in this instance, it is provided with an outwardly extending hub 44 which is secured to the driven shaft section 43 by means of a set screw 45 or other suitable device.

From the foregoing description it will be seen that the rotation of the drive shaft 11 will rotate the drive plate 9 and by reason of the spring plunger connections with the driven plate, will cause the latter to rotate, to turn either the extended hub D of the driven sprocket or the driven section 43 of the shaft and through the intermediacy of the sprocket chain C will drive the bearing rolls of the press. Whenever resistance is offered by the 100 baling rolls or the power devices which operate the same through the driven plate 15 of the dynamometer, the coil springs 25 will become compressed to the degree of torque being exerted, and the projections 33 of the 105 plunger mechanisms will move through the slots 32 and cam the ring 29 to move it axially of the shaft on the keys 31. Due to the shoe 36 engaging in the groove 35 of the ring, the shoe will be moved to one side, thereby 110 turning the crank 37 and rotating the pointer 42 relative to the graduations 41 to give a visible indication of the amount of torque being created in the press. As soon as this 115 torque diminishes, the springs 25 will return to their normal positions to return the rings 29 to its normal position to be again moved upon the slightest of torque.

As outlined in my above named copending application, I have discovered that such an 120 indicating mechanism can be employed to advantage for indicating, in terms of torque, not only the resistance offered to the rotation of the baling rolls, but for indicating the 125 density of the baled material at all stages of 130

its formation, and whenever excessive friction is being created in the bearings of the rolls or other portions of the power device.

It is well known that there is a normal torque in baling cotton, and this will turn the indicator to a certain point when bales of certain poundage are being formed. As explained in my copending application, this torque varies with different grades of cotton and under different atmospheric conditions. Some days it will be higher and some days lower, but having once determined within reasonable limits the position assumed by the indicator when baling particular cotton under existing atmospheric conditions, it is possible to keep an accurate check on the press; for after having turned out one bale and established a normal torque, it is found that as the baling proceeds, the indicator turns over considerably beyond the reasonable range of limits, it can then be assumed that there is something wrong with the press and excessive friction is being created by some of the parts. The press can then be stopped and the cause of excessive torque remedied. It will also be apparent that as the bale of material nears complete formation, the indicator hand or pointer 42 will indicate a certain amount of torque so as to apprise the operator as to when to discharge the bale from the press so that it will have the required density and poundage.

While I have described my improved dynamometer in connection with a baling press, it will be understood that I do not limit its uses to that art and that it can be effectively employed in any art in which torque determination is desired, or where a safety coupling is required. It is also to be understood that various changes as to the arrangement, size and shape of the various parts may be made without departing from the spirit of the invention or the scope of the appended claims.

45. What I claim is:

1. A device of the class described comprising a pair of rotatable members, yieldable means connecting them for relative turning movement, cam means encircling both of said members and actuated by said relative movement, and indicator means operated by said cam means.

2. A dynamometer comprising driving and driven disks arranged with an intervening space therebetween throughout their extent, yieldable means arranged in said space and connecting said disks to permit their relative turning movement, cam means encircling both of said disks and said space and actuated by said relative movement, and indicator means operated by said cam means.

3. A dynamometer comprising a pair of rotatable members, yieldable means connecting them for relative movement, a ring peripherally disposed relative to said members and

actuated by said relative movement, said ring having a cam slot, means on one of said members operating in said slot, and indicator means operated by said ring.

4. A dynamometer comprising a pair of rotatable members, yieldable means permitting their relative movement, a ring encircling said members and actuated by said relative movement, said ring having a cam slot, means on one of said members operating in said slot, 75 and indicator means operated by said ring.

5. A dynamometer comprising a pair of rotatable members, spring means connecting the same for permitting their relative turning movement, a ring peripherally disposed relative to said members and actuated by said relative movement, said ring having a diagonal slot, means carried by one of said members and operating in said slot, and indicator means operated by said ring. 80

6. A dynamometer comprising a pair of rotatable members, a spring restrained plunger including a bolt connecting said members and permitting their relative movement, a ring actuated by said relative movement and having a cam slot, a projection carried by said bolt operating in said slot, and indicator means operated by said ring. 85

7. In a dynamometer, a pair of rotatable discs, yielding means connecting the same and permitting relative turning movement, a rotatable and axially movable member mounted upon one of said discs and having a peripheral groove, a shoe operating in said groove, an indicator shaft, and a crank connecting 90 said shaft and shoe. 95

8. In a dynamometer, a pair of rotatable discs, spring means connecting the same and permitting their relative turning movement, a rotatable and axially movable member mounted upon one of said discs and having a peripheral groove, a shoe operating in said groove, an indicator stand having a set of graduations, an indicator shaft journaled in said stand and having a pointer cooperating 100 with said graduations, and a crank carried directly by said shaft and connected directly to said shoe. 105

9. A dynamometer comprising driving and driven members, a cage connected to said driven member and having slots, a plunger connected to the driving member operating in said cage and slots, a spring in said cage abutting said plunger and cage, a pin carried by said driving member, said plunger having an 110 eye receiving said pin, a cam member encircling said members and operated by their relative movement, and indicator means operated by said cam member. 115

10. A dynamometer comprising a pair of 120 relatively rotatable members, yieldable means connecting the same for relative movement, an indicator operating member actuated by said relative movement and having a cam slot, means carried by one of said members and ex- 125 130

tending parallel to the axis thereof, and a projection of said last-named means operating in said cam slot.

11. A dynamometer comprising a pair of 5 relatively rotatable members, spring means connecting the same for relative turning movement, an arcuated member rotatable with and movable axially of one of said members, said arcuated member having a slot, and 10 a radially projecting member carried by said other member and operating in said slot.

12. A dynamometer comprising a pair of 15 relatively rotatable discs, yielding means connecting the same for relative turning movements, a ring splined on the periphery of one of said discs and overlapping the periphery of the other disc, said ring having a cam slot, and means carried by said other member and operating in said slot.

20 13. A dynamometer comprising driving and driven members, a cage connected to said driven member, a plunger connected to the driving member and operating in said cage, a spring in said cage abutting said plunger, 25 a pin carried by said driving member, said plunger having an eye receiving said pin, said eye being provided with a projection, and a cam member having a slot receiving said projection and adapted to be operated by the relative movement of said driving and driven members.

14. A device of the class described comprising a pair of rotatable members, yieldable means connecting them for relative turning 35 movement, an annulus encircling both of said members, cam means for moving said annulus upon relative movement of said members, and indicator means operated by said annulus.

15. A device of the class described comprising a pair of rotatable members, yieldable means connecting them for relative turning movement, an annulus encircling both of said members, means for moving said annulus axially upon relative movement of said 45 members, and indicator means operated by said annulus.

16. A dynamometer comprising driving and driven members, a cage connected to said driven member and having slots, a plunger 50 connected to the driving member operating in said cage and slots, a spring in said cage abutting said plunger and cage, a pin carried by said driving member, said plunger having an eye receiving said pin, and said driven 55 member having an annular flange encircling said driving member.

In testimony whereof I have hereunto set
my hand.

ALEXANDER S. MACKENZIE.
